UNITED STATES PATENT OFFICE

GEORGE R. MEYERCORD, OF CHICAGO, ILLINOIS, ASSIGNOR TO HASKELITE MANUFACTURING CORPORATION, A CORPORATION OF NEW YORK

REFRIGERATOR LINING

Application filed April 21, 1928. Serial No. 271,705.

The present invention has for its object to produce a simple and novel lining for the refrigerating compartment in a refrigerator, which lining shall be composed in the main of vitreous material, while having a top composed of a material having a sanitary surface, but which shall be strong, tough and easily workable, so as to permit cooling coils, shelves or other things to be suspended therefrom.

The various features of novelty whereby my invention is characterized will hereinafter be pointed out with particularity in the claims; but, for a full understanding of my invention and of its objects and advantages, reference may be had to the following detailed description taken in connection with the accompanying drawing, wherein:

Figure 1 is a horizontal section through a refrigerator box lined in accordance with the present invention; and Fig. 2 is a vertical section, on a somewhat smaller scale.

Referring to the drawing, 1, 2, 3 and 4 are slabs of vitreous material forming respectively the bottom, the two sides and the back of a refrigerator lining. The top wall of the lining is made of a piece of metal-sheathed lumber 5.

In constructing the lining, the several slabs or panels are cut to the proper size so that when they are laid, flat face of one against the edge of another, they produce a box-like structure open on one side. The top panel, which consists preferably of a core of plywood sheathed on both sides with metal, has the marginal portion cut away on the underside, along the rear, to produce a lip 6 that will rest on the top edge of the back wall. The same expedient is also adopted at the sides. The sheathing on the underside or face of the metal-sheathed panel is bent inwardly over the shoulder at the base of the lip, as indicated at 7. The sheathing on the underside of the top panel may therefore be said to be provided with flanges to abut against the faces of the side and rear walls. The sheathing on the underside of the top panel is extended beyond the front end of the panel and is turned up, as indicated at 8. The width of the flap or extension 8 is con-

siderably greater than the thickness of the panel, so that the flap will project up beyond the top of the panel and serve as a lip through which fastening means may be driven as hereinafter explained.

In the process of assembling the various elements of the lining, the vitreous slabs and the metal-sheathed panel are set up relatively to each other as shown in the drawings. Wire mesh sheets 9 are cemented to the outer faces of the vitreous slabs, and then short pieces of wire netting are bent over the six corners of the box-like formation, as indicated at 10; these pieces being cemented to the larger sheets and to the top of the metal-sheathed panel. The wire mesh at the sides and at the bottom is continued beyond the free ends of the side and bottom slabs, to provide flaps 11, 12 and 13 that may be bent laterally.

After the lining has been completely assembled, it may be secured to a preformed front wall comprising a wooden frame 14 sheathed with metal 15. The flaps 8, 11, 12 and 13 are nailed or otherwise fastened to the rear face of the wooden frame. In the arrangement shown, nails 21 are driven through wooden strips 22 laid in the angles formed by the flaps with the adjacent wall members of the lining; thus avoiding any looseness in the connection between the lining and the front wall of the refrigerator. An outer casing or wrapper 16 is then applied to the front wall, forming an insulating space around the lining. This space, and the space above and below the lining, is then filled with insulating material 17 introduced in a plastic form, and top and bottom panels 18 and 19 are applied to complete the outer casing or shell.

It will be seen that the insulated box thus formed has a simply formed sanitary lining provided with a top wall to which supporting devices of various kinds may easily be attached. For example, shelves may be carried by suitable hangers depending from hooks of which one, indicated at 20, is illustrated. Cooling coils may be supported in the top of the box by means of brackets secured to the metal-sheathed panels by screws or otherwise.

While I have illustrated and described

with particularity only a single preferred form of my invention, I do not desire to be limited to the exact structural details thus illustrated and described; but intend to cover all forms and arrangements which come within the definitions of my invention constituting the appended claims.

I claim:—

1. A lining for a refrigerator comprising slabs of vitreous material arranged in contact with each other to form a bottom wall, a back and two side walls of a lining, a panel of metal-sheathed lumber engaged with the upper ends of the side and back walls to form the top of the lining, and elements cemented to the exterior of the lining to hold the parts together.

2. A refrigerator lining comprising slabs of vitreous material engaged with each other forming a bottom and a rear and side walls, a panel of metal-sheathed lumber engaged with the upper edges of said rear and side walls and forming the top of the lining, wire mesh sheets cemented to the outer sides of said slabs and said panel to secure them together, the wire mesh extending beyond the front ends of the side walls and the metal sheathing on the underface of the top panel extending beyond the front end of the top panel to provide flaps that may be bent laterally and be secured to the front wall of a refrigerator.

3. The combination with a refrigerator having a wooden front, of a lining in rear of and in contact with said front, the top wall of the lining consisting of metal-sheathed lumber, the sheathing on the underface of the top being continued up in engagement with said wooden front in the form of a flange to a point above said top, and fastening devices extending through said flange into said wooden front.

4. A refrigerator lining composed of vitreous sides back and bottom, and a metal-sheathed lumber panel forming the top, and means at the front of said lining for securing the same to the front wall of a refrigerator.

In testimony whereof, I sign this specification.

GEORGE R. MEYERCORD.
